UNITED STATES PATENT OFFICE.

GUSTAVUS E. KASTENGREN, OF SAN FRANCISCO, CALIFORNIA.

SPEED-MEASURE AND ALARM.

SPECIFICATION forming part of Letters Patent No. 555,775, dated March 3, 1896.

Application filed June 12, 1895. Serial No. 552,590. (No model.)

To all whom it may concern:

Be it known that I, GUSTAVUS E. KASTENGREN, of San Francisco, in the county of San Francisco and State of California, have invented a new and Improved Speed-Indicator, of which the following is a full, clear, and exact description.

The object of the invention is to provide a new and improved speed-indicator which is simple and durable in construction, very effective in operation, arranged to indicate the speed of a desired revolving part, and to sound an alarm when an excessive speed is reached, the said indicator being especially designed for vessels, cars, and other vehicles, engines, dynamos, and other machinery.

The invention consists of certain parts and details and combinations of the same, as will be fully described hereinafter, and then pointed out in the claims.

Reference is to be had to the accompanying drawings, forming a part of this specification, in which similar characters of reference indicate corresponding parts in both the figures.

Figure 1 is a front elevation, partly in section, of the improvement on the line 1 1 of Fig. 2; and Fig. 2 is a side elevation, in section, of the same on the line 2 2 of Fig. 1.

The improved speed-indicator is provided with a shaft A, on which is secured a pulley A', over which passes a belt A², connected with the revolving part the speed of which is to be indicated. The shaft A is mounted to turn in the lower end of a casing or frame B, and on the upper end of the said shaft A is secured a cross-piece C', forming part of a weight-governor C, provided with two spring bands C² and C³, pivotally connected at their lower ends with the outer ends of the cross-piece C'. The upper ends of the spring-bands C² and C³ are pivotally connected with an arm C⁴, mounted to rotate loosely at its middle on a pivot-pin D, attached to the lower end E' of a rack E, mounted to slide in suitable bearings in the frame or casing B.

On the spring-bands C² and C³ are held adjustable weights C⁵ and C⁶, respectively, by set-screws C⁷, and the said weights are provided with screw-rods C⁸, connected with each other by coil-springs C⁹, and a second set of screw-rods C¹⁰ is likewise attached on the said

weights and connected with each other by coil-springs C¹¹.

Now it will be seen that when the shaft A is rotated the governor C is actuated and the weights C⁵ and C⁶, owing to centrifugal force, are caused to fly outward in opposite directions, whereby the springs C¹¹ are extended, as the said springs are under constant pressure, and when the said weights have moved outward a certain distance, then the other springs C⁹ come into play, so as to take up the centrifugal force. The weights C⁵ and C⁶ in moving outward cause a downward pull of the arms C⁴, whereby a downward sliding of the rack E is produced, and as the said rack is in mesh with a pinion F' on a shaft F the latter is rotated by the action of the centrifugal governor C. The outer end of the shaft F is provided with a pointer G, indicating on a dial H, so that the rotary motion of the shaft F is indicated by the pointer G on the graduation of the dial H—that is, the speed of the part connected with the pulley A' is thus measured.

On the shaft F is also secured a second indicating-wheel I, which serves as a fly-wheel, and the shaft F is provided on its peripheral surface with a graduation I', which can be read through a glass J in the top of the frame B or casing B. It is understood the speed read by the pointer G on the dial H corresponds with that read by the operator through the glass J on the graduation I'. 75

On the rack E is held adjustable a bar K, provided with the elongated slots K', through which pass the set-screws K², so as to permit of shifting the bar K vertically on the rack E. The lower end of the bar K is adapted to move in contact with a spring L, projecting from one end of a lever N, fulcrumed at N' on an insulating-plate B' held in the casing B. The upper end of the lever N is drawn on by a spring N², so as to hold the said lever out of normal contact with the contact-plates P'. One of the contact-plates P' is connected with an alarm P of any approved construction, and the other contact-plate P' is connected with a battery O, or other suitable source of electrical supply, so that when the rack E is drawn downward by the action of the centrifugal governor C beyond a certain

predetermined point then the bar K engages the spring L to cause the lever N to swing and make contact with the contact-plates P'. The lever N in doing so connects the battery 5 O with the alarm P, and consequently the alarm is sounded to call the attention of the engineer or other person in charge to the fact that the part or machine the speed of which is to be indicated is running beyond a normal rate of speed.

Thus it will be seen that the device described not only acts as an indicator for the speed, but also as an alarm in case of excessive speed.

15 Having thus fully described my invention, I claim as new and desire to secure by Letters Patent—

1. A speed-indicator, comprising an indicator-shaft carrying a pointer adapted to indicate on a dial, a pinion secured on the said shaft, a rack fitted to slide and in mesh with the said pinion, a weight-governor connected with the said rack and driven from the part the speed of which is to be indicated, the 25 said weight-governor being provided with spring-bands, weights held on the bands, and springs for connecting the weights with each other, substantially as shown and described.

2. A speed-indicator, comprising an indicator-shaft carrying a pointer adapted to indicate on a dial, a pinion secured on the said shaft, a rack fitted to slide and in mesh with the said pinion, a weight-governor connected with the said rack and driven from the part 35 the speed of which is to be indicated, the said

weight-governor being provided with pivoted spring-bands, weights held on the bands, and springs for connecting the weights with each other, one of the said springs being under constant tension, substantially as shown and described. 40

3. In a speed-indicator, the combination with an indicator-shaft carrying a pointer adapted to indicate on a dial, a pinion on said shaft, and a sliding rack meshing with the 45 pinion, of a weight-governor driven from the part, the speed of which is to be indicated, the said governor, comprising cross-pieces, one of which is pivoted to the rack, springs pivoted at their ends to the cross-pieces, adjustable weights on the springs, and coil-springs having their ends connected to the said weights, substantially as described. 50

4. In a speed-indicator, the combination with an indicator-shaft carrying a pointer 55 adapted to indicate on a dial, a pinion on the shaft, a sliding rack meshing with the pinion, and a weight-governor connected with the rack and driven from the part, the speed of which is to be indicated, of a bar adjustably secured to the rack, an electric alarm, and a pivoted and spring-pressed lever provided with a contact-spring at one end with which spring the lower end of the said bar is adapted to engage, substantially as described. 60 65
